United States Patent Office.

DAVID GREENE HASKINS, OF CAMBRIDGE, MASSACHUSETTS.

Letters Patent No. 70,207, dated October 29, 1867.

IMPROVEMENT IN GAS-COOKING APPARATUS.

The Schedule referred to in these Letters Patent and making part of the same.

TO ALL WHOM IT MAY CONCERN:

Be it known that I, DAVID GREENE HASKINS, of Cambridge, in the county of Middlesex, and State of Massachusetts, have invented a new and improved Gas-Cooking Apparatus, of which the following is a full, clear, and exact description, reference being had to the accompanying drawings, making a part of this specification, in which—

Figure 1 represents a perspective view of my improved apparatus, showing the inside.

Figure 2 is a vertical section of the same.

Figures 3, 4, 5, and 6 are details of devices employed in the apparatus.

The object of my invention is to provide a simple, economical, and efficient apparatus for cooking purposes, in which the flame of gas, or that produced from any of the oils or burning-fluids, is employed as fuel, in such a manner that the cooking, etc., shall be effected by radiation instead of the direct action of the heat from such a flame, as in the gas-cooking apparatus in general use; and the invention consists of a case or box, of any desired shape or size, formed of two plates or sheets of metal on all its sides except the front, with a space between such plates through which the products of combustion pass from the flame to the chimney or flue, which space, on the under side, is filled, more or less compactly, with layers of wire netting, as used in my other patented heating apparatus, and for the purposes of detaining and radiating the heat.

In gas-cooking stoves in common use, as far as I am aware, the cooking is produced by heat arising from the direct action of the flame upon the articles to be cooked, or upon the utensils in which the same are cooked, and then the products of combustion from the gas, together with the fumes arising from the articles cooked, are allowed to escape into the room or apartment in which the cooking is being done.

In my apparatus the cooking is effected by the radiation of the heat from the action of the flame and products of combustion on the diaphragm and inner casing, the said flame and products of combustion not being allowed to enter the apartment of the apparatus in which the articles to be cooked are placed, but, after imparting their heat, are passed off to the chimney, together with the smoke and fumes from the cooking viands.

Referring to the drawings, fig. 1 represents a perspective view of my apparatus, with the doors open. It is constructed of a double casing, *a c*, of sheet metal on all its sides, as well as at top and bottom, with a space between the two casings, as shown in section in fig. 2. In the bottom of the inner casing is an opening for the reception of a kettle, *k*, or any other culinary article for boiling or cooking purposes. When it is desired to close the said opening a cover, *e*, as shown in figs. 3 and 4, is employed, so as to preserve an even surface on the bottom of the apparatus. The said cover *e* is provided with a diaphragm or secondary plate, *e'*, attached to its under side by a central pin, or by pins arranged nearer the edges of the same, which serves to absorb and diffuse the heat derived from the flame of the burner below. On the under part of the apparatus is a cylinder, *b*, open at its lower end, and attached to the outer casing at its upper end, as shown in fig. 2. This cylinder communicates only with the space between the two casings of the apparatus, so that the heat, or products of combustion from the flame of the gas, etc., will pass off from the cylinder *b*, through the space around the sides and top of the apparatus, to the flue *f* leading to the chimney.

The space at the rear of the apparatus is separated from that at the sides by a diaphragm or partition, so arranged that the products of combustion will pass up through the space on each side of the apparatus, over the top of the same, and down the rear space to the flue *f*, as shown by the arrows, by which means the entire inner compartment will be heated. Ledges *s* are fixed to the sides of the inner compartment, to support shelves, upon which articles to be cooked are placed.

Fig. 5 and 6, represents a form of broiler or gridiron to be used with my apparatus. It is formed with metal rods attached to the upper edges of a pan, so as to fit in the opening in the inner compartment. *h* is a valve or cover, placed over an opening in the rear of the inner casing, to permit the escape of steam or fumes arising from the articles being cooked. A similar opening and cover are arranged in the top of the inner compartment, for the same purpose. *k* is a cover, placed on an opening in the top of the outer casing, which cover may be removed, and a kettle, dish, or other article may be placed in the opening, for the purpose of heating the same. There may also be a double hearth attached to this stove, with holes provided with covers, for placing pots or kettles, with separate burners under them, the products of combustion passing between the two

surfaces of the hearth to the space around the oven, or directly into the smoke pipe. In the space between the two casings may be placed wire gauze, or other heat-radiating material, as provided for in a patent granted to me on April 10, 1866, and numbered 53,820.

My apparatus may be very cheaply constructed. The two casings may be made of different sorts of metal, the inner casing to be of some heat-conducting material, and the outer of a non-conducting material.

Having thus described my invention, what I claim as new, and desire to secure by Letters Patent, is—

1. A gas-cooking apparatus, formed with the double casings *a* *c*, filled, as described, with wire netting, in combination with the combustion-chamber *b* and exit-flue *f*, the inner casing being provided with a hole, for the reception of a kettle or other culinary vessel, and with openings and covers *h*, for the escape of steam, etc., substantially as specified.

2. I claim the combination of the metal plate or cover *e*, provided with the diaphragm *e'*, with the perforated inner casing *c* and the combustion-chamber *b*, as set forth.

In testimony whereof I have signed my name to this specification in the presence of two subscribing witnesses.

DAVID G. HASKINS.
